(57) **CLAIM**

The ornamental design for a glow stick multi-purpose safety device, as shown and described.

DESCRIPTION

FIG. 1 is a perspective view of the glow stick multi-purpose safety device according to the present design;

FIG. 2 is a right side elevation view of the design of FIG. 1;

FIG. 3 is a left side elevation view of the design of FIG. 1;

FIG. 4 is a top plan view of the design of FIG. 1;

FIG. 5 is a bottom plan view of the design of FIG. 1;

FIG. 6 is a front elevation view of the design of FIG. 1; and,

FIG. 7 is a rear elevation view of the design of FIG. 1.

1 Claim, 2 Drawing Sheets

FIG. 7
